CARRIAGE AND BUCKET FOR INCLINABLE BOOMS

Rudolph F. Lindow, Wauwatosa, Wis., assignor to Chain Belt Company, Milwaukee, Wis., a corporation of Wisconsin

Application May 2, 1946, Serial No. 666,659

5 Claims. (Cl. 214—59)

1

This invention relates to improvements in a bucket and carriage for an inclinable boom used with a paving or concrete mixing machine. This invention enables a paver to be adapted to divers conditions and usages with far greater flexibility than was heretofore possible. The invention also permits the automatic leveling and stabilizing of a concrete carrying bucket associated with a boom, regardless of the angle to which the boom may be inclined. Also the tripping mechanism which opens and closes the discharge door of the bucket is operable in any position of the boom without changes necessitating strenuous efforts; actually the adjustment is effortless.

The use of an inclined boom has enhanced the value of a paving machine greatly. One of these advantages is at once apparent when a paving machine is operated on articulated terrain where the boom is adjusted to accommodate the rise and fall of the terrain. Another use is greatly appreciated in the construction of buildings and other like structures, for a paver with such a boom and bucket can be used to deliver mixed concrete to elevated structures which could only be otherwise reached by expensive elevator systems.

Prior attempts to provide an inclinable boom and the bucket used therewith have resulted in cumbersome structures. These structures also have the disadvantage of necessitating arduous labor for the change-over in the suspension of the bucket from one position of the boom to the next. For, in any given position the attachment of the bucket to the boom was fixed. These disadvantages have sometimes outweighed the commercial feasibility of such a paving machine.

It is the object of this invention to provide a readily adjustable bucket which will conform to inclinations of a boom.

Another object of the invention is to provide for an inclinable boom, a self-conformable bucket and mounting thereon.

It is also an object of this invention to provide a conformable door operating mechanism for a bucket which is constructed to handle concrete and similar materials.

Another object of this invention is to provide a stabilized conformable bucket and carriage for an inclinable boom.

Still another object of the invention is to provide a carriage and bucket of simple structure for an inclinable boom.

The invention is thought to be best illustrated in the selected embodiment shown in the following figures:

2

Fig. 1 is a side elevation of a crawler type paving machine with its boom and bucket in the horizontal position, shown in full lines and its boom and bucket in an inclined position shown in broken lines;

Fig. 2 is a side elevation of the carriage and concrete distributing bucket mounted on a boom which is inclined. The full lines show the bucket with its door in the closed position, and the broken lines show its door in the open position;

Fig. 3 is an end view of the boom and carriage shown in Fig. 1;

Fig. 4 is a sectional view of the tripping device taken along the lines 4—4 of Fig. 3;

Fig. 5 is a sectional view of the stabilizing means; and

Fig. 6 is a sectional view of another form of the stabilizing means.

Referring to the drawings, and particularly to Fig. 1, it will be noted that the paving machine 20 is of conventional form and is well known in the art. Attached thereto is a boom 23, said boom is pivotally mounted on the paver by means of the pivotal connection 24 for angular movement relative to the horizontal and vertical, and the supporting pivot 21 is rotatably mounted for lateral movement of the boom. Mounted on the boom 23 is the carriage 22. The carriage traverses the boom by means of the rollers 25 which engage ledges on the boom on either side thereof. Connected to the rollers 25 are the side plates 26 which are rigidly connected to the shafts 27 and 42 thus forming a stable structure capable of traversing the boom. The cable 28 is connected to the carriage at 29, and this supplies the traversing means along with the cable 30.

Pivotedly suspended from the carriage 22 is the bucket for containing concrete 31. This is mounted to the carriage by means of the straps 32 which are rotatably mounted on the shaft 27 to permit the free movement of the bucket. The bucket has a pivotal discharge door 33 located at the bottom thereof. It further has door actuating means 34 which consists of a linkage of levers, an arm 35, a toggle 36, a bell crank 37, the rod 38 and lever 39. The lever arm 39 is secured to a sleeve 43 the function of which will be subsequently described.

The bucket 31 is stabilized by means of a hydraulic stabilizer 40, it is pivotally attached to the bucket on the rod 41 and pivotally attached to the carriage on the rod 42. It will be described in greater detail in relation to Figs. 5 and 6.

Referring to Figs. 3 and 4, it will be noted that mounted on the shaft 27 are three sleeves. The

sleeve 43 is rotatable, but substantially axially fixed. Its inner face 44 is serrated or jaw-like, and this face is also counterbored to form a recess 45 to engage the spring 46. Adjacent to the sleeve 43 is a similar sleeve 47. The face 44' is serrated or jaw-like, matching the face 44 that it might engage therewith. This face is also counterbored to receive the spring 46. The spring bears against the two sleeves and this action keeps the two jaws disengaged when the bucket door is not operated. Mounted on sleeve 47 is a lever arm 48 on which is rotatably mounted a roller 49; this is for engagement with the cam members 50 and 51 mounted on the boom 23. The lever 48 may also be motivated by other means, such as a tag line.

One end of the sleeve 47 has a cam surface 52. This is for engagement with a similar surface 53 on one face of the sleeve 54. These cam surfaces are hardened by known processes to minimize wear and are shown apart from each other for purposes of illustration; actually they bear securely on each other. As the lever 48 is rotated, the sleeve 47 is axially displaced toward the sleeve 43. This is by action of the two cams 52 and 53 on each other. The sleeve 54 is nonrotatable. However, it is resiliently mounted by means of the springs 55; this is necessary for in the event the jaws of sleeves 47 and 43 should not mesh, the sleeves will yield so as not to unduly strain the structure of the jaws and carriage 26. The combined effort of resistance of the springs 55 is considerably greater than the separating force exerted by the spring 46 so that the sleeve 47 will be forced into engagement with the sleeve 43 when it is rotated.

It will be noted that when the lever 48 is rotated in a counterclockwise direction (see Fig. 2) the lever mechanism is actuated to close the door 33 and throw the toggle 36 over center to lock said door. As the carriage is drawn up along the boom the lever and roller mounted thereon engages the cam 50 which rotates the said lever in a clockwise direction actuating the linkage system to throw the toggle 36 over center and further to cause the opening of the door 33. When the bucket returns to loading position at the inner end of the boom, the roller 49 strikes the cam 51, which closes the door.

From the foregoing it will be observed that the roller 49 constitutes tripping means which will always be in position, regardless of the angle of boom inclination, to engage the cam trips 50 and 51 and to cause the proper action of the bucket door; the bucket however may be maintained in horizontal position by pivoting relative to its carriage since the sleeve 43 may rotate independently of the sleeve 47.

Referring to Fig. 5 it will be noted that it is a sectional view of the stabilizing means 40. It comprises a cylinder 62, a connecting member 63 on the cylinder, and a piston 64 connected to a shaft 65 extending within the cylinder. A connecting means 66 is mounted on one end of the shaft 65. The shaft 65 has a packing 67 to retain the fluid 68 which fills the cylinder. In the piston 64 are several small holes 69. These permit the fluid 68 which is substantially incompressible to pass from one compartment to the other, thus varying the distance between the two holding means 63 and 66. Thus it is apparent that when the bucket 31 is pivoted about the shaft 27 the stabilizing means 40 will readily conform to such movement as the stabilizing means may be slowly extended or contracted.

Also as the carriage is drawn along the inclined boom and suddenly stopped the stabilizing means will check and impair any free rotation about the shaft 27, for the oil flow through the piston 64 is at a low rate; hence axial movement of the stabilizing means is considerably impaired.

Fig. 6 shows an alternate arrangement of the stabilizing means. It is composed of a cylinder 70, connecting means on said cylinder 71, and a piston within the cylinder 72, also a shaft 73 connected to said piston. Connecting means 74 is attached to the piston shaft. The piston 72 is so disposed within the cylinder 70 so as to form two compartments 75 and 76 which are in hydraulic communication by means of piping 77. In communication with the piping 77 is a manually operated valve 78, and in both compartments and also in the communication system there is an incompressible fluid 69 such as conventional hydraulic oil. It will be understood that as the valve 78 is operated permitting fluid under pressure to flow from compartment 75 to compartment 76 the distance between the centers of the connecting points 71 and 74 is increased, or the converse may be done. The use of this adjustable stabilizing means has some advantages in that it permits more rapid leveling of the bucket 31. However, the invention is not necessarily limited to the stabilizing means shown in Figs. 5 and 6.

The embodiment shown is the one selected to best delineate the invention. However, it is not necessarily limited to its precise details, but is to be limited only by the clear import of the following claims. Having thus described the invention, what is claimed is:

1. Apparatus for supporting a bucket and actuating the bucket door comprising a boom inclinable at various angles, a carriage traversably mounted on the boom, a bucket pivotally suspended from the carriage, bucket stabilizing means connecting the bucket and the carriage enabling the bucket to pivot on the carriage when the inclination of the boom is adjusted and maintaining the bucket against free movement after such adjustment, a trip on the boom, tripping means mounted on the carriage engageable with the trip, means for actuating the door in response to action of the tripping means, and clutch mechanism engageable upon initial movement of said tripping means to couple said tripping means to said door actuating means, whereby subsequent movement of said tripping means effects actuating of said bucket door, said clutch mechanism being at other times disengaged, thereby permitting pivoting of the bucket relative to its carriage in response to adjustment of the boom without changing the position of the tripping means relative to the boom trip.

2. Apparatus for supporting a bucket and actuating the bucket door comprising a boom inclinable at various angles, a carriage traversably mounted on the boom, a bucket pivotally suspended from the carriage, bucket stabilizing means connecting the bucket and the carriage enabling the bucket to pivot on the carriage when the inclination of the boom is adjusted and maintaining the bucket against free movement after such adjustment, a trip on the boom, tripping means for the bucket door engageable with the trip and means for actuating the door in response to action of the tripping means, said last mentioned means being journaled on the bucket pivot means and making engagement with the door actuating means only

when the tripping means is actuated whereby the bucket may be pivoted relative to the carriage without disturbing the position of the tripping means relative to the boom trip.

3. A carriage and bucket for an inclinable boom comprising means for supporting the bucket on the carriage enabling the bucket to be adjusted whereby it may hang vertically despite the inclination of the boom, said bucket

having a bottom door and mechanism for opening the same, a trip mounted on the boom, tripping mechanism mounted on the carriage engageable with the trip to cause movement thereof, means responsive to movement of said tripping mechanism to cause engagement of the tripping mechanism with the door operating mechanism, and means maintaining disengagement of said mechanisms when the trip is not engaged whereby the bucket may be adjusted relative to the carriage without disturbing the relation of the tripping mechanism to the boom trip.

4. A carriage and bucket for an inclinable boom comprising means supporting the bucket on the carriage enabling the bucket to be adjusted whereby it may hang vertically despite the inclination of the boom, said bucket having a bottom door and mechanism for opening the same, a shaft mounted on the carriage, a bucket door tripping member mounted on said shaft engageable with tripping means positioned on the boom, said member having a clutch face, a second member mounted on the shaft having a clutch face engageable with the clutch face of the first member, said second member being connected to the bucket door actuating mechanism, a third member mounted on the shaft having a cam face engageable with the first member to maintain the position thereof and to cause engagement of

the clutch faces when the first member is engaged by the tripping means, whereby the bucket door is moved, and yieldable means normally maintaining said clutch faces out of engagement whereby the position of the bucket may be adjusted with respect to the boom without disturbing the position of the first member relative to the tripping means.

5. A carriage and bucket for an inclinable boom comprising a movable carriage mounted on the boom, a bucket pivotally mounted on said carriage having a discharge door, bucket door operating mechanism connected to the discharge door of said bucket, tripping means mounted on the carriage engageable with the door operating mechanism to produce movement of the bucket door, and means arranged to produce engagement between the tripping means and the bucket door actuating mechanism when the tripping means is moved, said means being inoperable when the tripping means is in one of its positions, whereby the bucket may be moved relative to the carriage without producing movement of the tripping means, and stabilizing means connecting the bucket and carriage.
